HONING TOOL

Maurice N. Prange, Highland Park, Mich.

Application May 11, 1944, Serial No. 535,122

8 Claims. (Cl. 51—184.3)

1

The invention relates to rotary honing tools of the type employed for the honing of engine cylinders and for similar work.

It is the primary object of the invention to obtain a construction which is suitable for honing small diameter cylindrical surfaces such, for instance, as a diameter of $\frac{1}{8}$ of an inch.

It is a further object to obtain means for holding the abrasive members or stones which will permit of adjustment of the same during the continuance of the honing operation. With these objects in view the invention consists in the construction as hereinafter set forth.

In the drawings:

Fig. 1 is a central longitudinal section partly in elevation through my improved honing tool;

Fig. 2 is a cross section on line 2—2, Fig. 1;

Fig. 3 is a similar view on line 3—3, Fig. 1;

Fig. 4 is a longitudinal section through one of the stones;

Fig. 5 is a cross section thereof;

Fig. 6 is a plan view thereof;

Fig. 7 is a side elevation of one of the cam members detached;

Fig. 8 is a plan view thereof;

Fig. 9 is a section on line 9—9, Fig. 1;

Fig. 10 is an elevation of the members shown in Fig. 9; and

Fig. 11 is an elevation of the tool.

Many constructions of honing tools which are used for large diameter work, such as engine cylinders, are not adapted for small diameter work. This is for the reason that there is not sufficient available space for the elements of the structure which requires redesigning the same. In particular, the abrasive elements or stones must be of very small dimensions, must be securely held in position during the performance of the work and capable of radially outward adjustment. To comply with such conditions, I have devised the following construction. A is a cylindrical body member of a diameter less than that of the bore to be honed being provided at one end with the reduced diameter threaded portion B for engagement with a threaded socket C of the rotary shaft D. The member A has formed therein a plurality of longitudinally extending channels E and is further provided with a plurality of longitudinally spaced annular bands F surrounding and secured to the same. The spaces between these bands and within the channels E are adapted to receive the abrasive members or stones G. Each of these is provided with holding means comprising a flexible member H preferably of fabric which is cemented to the bottom and one side of the stone. Portions H' and H² of this fabric extend beyond the opposite ends of the stone, the portion H' having an aperture H³ therethrough for engaging a pin F' extending radially inward from one of the bands F. This will hold the stone from longi-

2

tudinal movement while permitting radial movement. Within each of the channels E and inside of the stones G is a longitudinally extending cam member I. This is fashioned to cooperate with the stones G forming a supporting bearing therefor and a means for effecting a radially outward adjustment. As shown, the member I is provided with inclines or wedge faces I' for engaging correspondingly inclined bottom faces of the stones G. Also, to form a firm support or abutment for the stone holding the same from any rocking movement, the center portion of the member I is channeled or cut away at I² leaving a pair of laterally spaced wedge faces I' for each of the stones G. Within the channel I² is secured a spring finger J which bears against the projecting portion H² of the holder to retain the same and the stone within the channel E.

To provide for adjusting the stones during the continuance of the honing operation, I have provided means for moving the members I longitudinally in the channels E while the holder A is rotating. This means comprises a collar K surrounding the inner end portion of the member

A slightly reduced in diameter to form a shoulder K', the collar being arranged between this shoulder and the socket C. The inner surface of the collar is screw-threaded to engage threaded portions I³ on the inner ends of the members I so that rotation of the collar will effect a simultaneous longitudinal adjustment of all of the members I. A collar L is externally mounted on the socket member C and is secured thereto by radially extending pins M passing outward through

inclined slots L' in the collar. Springs L² are placed in these slots to abut against the pins M normally holding the collar in fixed position on the member C but permitting a limited relative rotary adjustment by compressing the springs L².

The collar L is further provided with one or more pawls N for engaging an annular series of ratchet teeth O on the collar K. The arrangement is such that when the collar L is relatively rotated in a direction to compress the springs L², the pawls N will be engaged with the registering ratchet teeth O and will rotate the collar K. However, the return movement of the collar L by the reaction of the spring L² will disengage the pawls from the ratchet teeth without imparting any reverse rotary movement to the collar K.

With the construction as described, when the tool is engaged with the bore to be honed, the stones G are sufficiently withdrawn radially inward to permit of such engagement. They may then be adjusted radially outward by successive oscillatory movements of the collar L, each of which will rotate the collar K and through the threads I³ will move the cam members I longitudinally in the channels E. This will cause the wedge portions I' to move the stones H outward,

while the members H' and pins F' will hold said stones from any longitudinal movement. After suitable adjustment of the stones is made, the tool is rotated and longitudinally reciprocated in relation to the work by a corresponding movement of the shaft D. Whenever it is necessary to further adjust the stones radially outward, this may be accomplished without stopping the rotation as the operator may merely place his hand in contact with the outer surface of the collar L frictionally retarding the same. This will effect a relative rotation of the collar on the socket member C and through pawls N and ratchet teeth O will produce a similar relative rotation of the collar K. When the hold on the collar L is released the spring L² will return it to normal position after which the operation may be repeated if necessary. It will be understood that the outer faces of the stones H are cylindrical segments corresponding to the cylindrical surface which is honed and, by reason of the spaced wedge bearings I', the abrasive face of the stone is held concentric with the axis of the tool.

What I claim as my invention is:

1. A honing tool comprising a longitudinally channeled rotary holder, an abrasive stone in said channel, a longitudinally movable cam member in said channel forming a backing for said abrasive member, an apertured fabric tab directly secured to and projecting beyond one end of said abrasive member, and a detent on said holder for engaging the aperture of said tab to hold said abrasive member from longitudinal movement while permitting radial movement by said cam.

2. In a honing tool, the combination with a longitudinally channeled rotary holder and a cam member longitudinally movable in said channel, of an abrasive stone provided with a flexible fabric tab directly secured thereto and projecting beyond an end thereof, and a detent on said holder engaging said tab to hold said stone from longitudinal movement while permitting radial adjustment by said cam member.

3. In a honing tool, the combination with a longitudinally channeled rotary holder and a longitudinally movable cam member in said channel, of an abrasive stone also engaging said channel and provided with a flexible member secured to the inner face thereof and projecting beyond the opposite ends to form tabs, a detent on said holder for engaging one of said tabs to hold said stone from longitudinal movement and a resilient member on said cam for engaging the other tab.

4. In a honing tool, the combination with a longitudinally channeled rotary holder and a longitudinally movable cam member in said channel, of an abrasive stone, a fabric member secured to one face and one side of said stone and projecting beyond the ends thereof to form flexible tabs, one having an aperture therein, a detent on said holder for engaging said apertured tab and a resilient finger on said cam member for engaging the other tab.

5. In a honing tool, the combination with a rotary holder having a plurality of circumferentially spaced longitudinally extending channels therein, of an abrasive stone in each of said channels anchored against longitudinal movement while permitting radial movement, a longitudinally movable cam member in each of said channels eccentric to the axis of said rotary member forming a backing for said abrasive stone, the end of said cam member being transversely threaded, a collar on said rotary holder threadedly engaging the threaded ends of all of

said eccentric cam member, and means for relatively rotating said collar on said holder during the rotation of the latter to adjust said cam member longitudinally and said stone radially.

6. A honing tool comprising a rotary cylindrical holder having a plurality of longitudinally extending channels therein, longitudinally spaced bands surrounding and secured to said holder, abrasive stones located in said channels in the spaces between said bands, a flexible apertured tab secured to and projecting beyond one end of each stone beneath the adjacent band, an inwardly projecting detent on said band engaging said aperture, a cam member extending longitudinally in each of said channels forming a backing for the stones therein, the inner ends of said cam members having transverse threads on the outer faces thereof, a collar surrounding said cylindrical holder internally threaded to engage the threads on said cam members, and means operable during the rotation of said tool for relatively rotating said collar to simultaneously adjust said cam members longitudinally in said channels effecting the radially outward adjustment of said stones.

7. In a honing tool, the combination with a longitudinally channeled rotary holder, of a member longitudinally movable in said channel provided with laterally spaced cam portions, an abrasive stone also in said channel seated against said laterally spaced cam portions to be held thereby against rocking, flexible means for holding said stone from longitudinal movement in said channel while permitting radial movement, and means for adjusting said first mentioned member longitudinally to effect said radial movement of the stone.

8. A honing tool comprising a rotary cylindrical holder having a plurality of longitudinally extending channels therein, a plurality of spaced annular bands surrounding and secured to said holder, a longitudinally extending member within each of said channels provided with laterally spaced cam portions opposite each space between said bands, an abrasive stone within each channel in the space between said bands, a flexible member secured to the under face of each stone and projecting beyond opposite ends thereof to form tabs, one of said tabs being apertured and extending beneath the adjacent band, a detent on said band engaging said aperture, a resilient finger secured to said longitudinally extending member and bearing against the oppositely extending tab to hold the stone against said cam portions, the lateral spacing of which hold said stone against rocking, and means for adjusting said longitudinally extending members longitudinally within said channels to effect the simultaneous radially outward movement of said stones.
